Des. 241,783

Patented Oct. 5, 1976

241,783

CARRYING CASE FOR A CAMERA AND ACCESSORIES OR THE LIKE

Sanford Sykes, 22201 Burbank Blvd.,
Woodland Hills, Calif. 91364

Filed Mar. 6, 1975, Ser. No. 555,874

Term of patent 14 years

Int. Cl. D3—02

U.S. Cl. D87—5 E

Fig. 1

Fig. 2

Fig. 3

Fig. 4

Fig. 5

FIG. 1 is a perspective view of a carrying case for a camera and accessories or the like showing my new design;

FIG. 2 is a right end elevational view;

FIG. 3 is a rear elevational view;

FIG. 4 is a top plan view; and

FIG. 5 is a bottom plan view.

I claim:

The ornamental design for a carrying case for a camera and accessories or the like, substantially as shown and described.
